[57] CLAIM

The ornamental design for an incubator for hatching eggs, as shown and described.

DESCRIPTION

FIG. 1 is a perspective view of an incubator for hatching eggs, showing my new design;

FIG. 2 is a top plan view thereof;

FIG. 3 is a side-elevational view thereof; and

FIG. 4 is a bottom plan view thereof.

The conventional electric cord has been broken away in FIGS. 1 and 3 and omitted from FIG. 2 for convenience of illustration.
